UNITED STATES PATENT OFFICE.

LOUIE A. HOLST, OF COLUMBIA, SOUTH CAROLINA.

DRIFTING DEVICE FOR LOCOMOTIVES.

1,331,013.

Specification of Letters Patent.

Patented Feb. 17, 1920.

Application filed May 3, 1918. Serial No. 232,359.

To all whom it may concern:

Be it known that I, LOUIE A. HOLST, a citizen of the United States, residing at Columbia, in the county of Richland and 5 State of South Carolina, have invented certain new and useful Improvements in Drifting Devices for Locomotives, of which the following is a specification.

My invention relates to a drifting device 10 for steam locomotives and while it generally aims to provide a novel, improved and more practical construction, yet a principal object is to so construct the apparatus as to exclude cold air, sparks, smoke and other matter 15 from the valves and cylinders, during drifting of the locomotive in order to decrease the wear on the operating parts.

Other particular objects will become apparent as the description progresses herein- 20 after and as considered in connection with accompanying drawings illustrating my present preferred embodiment.

In the drawings:—

Figure 1 is a longitudinal sectional view 25 of the improved apparatus.

Fig. 2 is a cross sectional view on the line 2—2 of Fig. 1, and

Fig. 3 is a fragmentary longitudinal sectional view through a modified form.

30 Referring specifically to the drawings, and first to Figs. 1 and 2, 4 designates a pipe or conduit which is in communication with that part of the steam boiler of a locomotive whereby dry steam is admitted. This pipe 35 leads a portion of the said dry steam to a valve chamber 5 having a suitable valve, like the cylindrical valve 6, slidably longitudinally therein.

The chamber 5, in the embodiment shown, 40 is rigidly mounted on a cylinder 7, supported by a suitable base as at 8. Pipe 4 leads directly to a steam chest 5' which supplies steam to opposite sides of the cylinder 6 through ports 4^a and 4^b. An oil cup or 45 lubricator 4^c is fastened to pipe 4 for the supply of lubricant therethrough to the piston 6 and cylinder 5.

In the lower wall of the chamber 5 and the upper wall of cylinder 7 are registering 50 ports 9 through which the steam may pass to the cylinder 7. An arm 10 depends rigidly from the valve 6 and is connected to a rod 11 of a piston whose head is shown at 12 and slides longitudinally of the cylinder. This 55 head 12 moves to the same extent as valve 6.

Piston rod 11 may extend exteriorly of the cylinder and be supported by and slidably in a bearing 13 extending from an end wall 14 of the chamber. Drain cocks 8^a may be provided for cylinder 5 whereby steam condensing into water therein may be removed and freezing in winter avoided. The other end wall of the cylinder is not air tight. It is shown at 15 and may have one or more ports 16 therein communicating with the atmosphere. Secured to the end wall 14 is a pipe or conduit 17 which is in communication with the steam chest of the engine. A drain cock 7' is secured to cylinder 7.

Preferably the chamber 5 is detachably 70 bolted as at 18 to cylinder 7 and the arm 10 is rigidly connected to the valve 6, and removably extends into a pocket 19 integral with the rod 11.

Steam is always present in chamber 5 in 75 view of its communication with the boiler by means of pipe 4. However, when the locomotive is drifting, the engineer having shut off the supply of steam from the steam chest of the engine, the pistons in the cylinder traveling back and forth in the engine, create a vacuum. By means of pipe 17 which is connected at the other end to the steam chest of the engine, piston 12 is sucked to the right in Fig. 1. This action 80 moves valve 6 to the right in chamber 5 by means of arm 10 which is connected to rod 11 and admits steam to cylinder 7 through port 9 and from the cylinder the steam flows 85 through pipe 17 to the steam chest of the engine. 90

As soon as the steam admitted to the steam chest of the engine creates a pressure it backs up through pipe 17 and into cylinder 7 and forces piston 12 to the left in 95 Fig. 1.

Valve 6 during this movement covers port 9 and cuts off the supply of steam to cylinder 7 and a vacuum is again created through pipe 17. The device thus automatically responds. In this manner, the steam admitted into the cylinders of the engine destroy the vacuum before the piston in the locomotive cylinder fully moves to release position.

Head 12 may be of any preferred construction and secured in any desired manner to the rod 11. However one or more piston rings 20 may be provided and a nut 21 may secure the head on the rod. In order to keep the parts in proper relation, rod 11 is 110

preferably square and slides through a correspondingly shaped opening in the bearing 13.

In some instances I may employ a valve in lieu of valve 6, which is rectangular in shape. To this end such a valve as that shown at 6^a in Fig. 3 may be used, and the steam chest 5^a and chamber 5^b, equivalent of the chamber 5, may be shaped to suit.

10 Other changes may be resorted to within the spirit and scope of the invention.

I claim:—

15 In combination with the steam chest of an engine, a steam chamber having an elongated opening therein, a cylinder detachably connected to the steam chamber and provided with an elongated opening registering

with the opening in the chamber, a valve 20
slidable in the steam chamber and adapted to open and close the elongated opening
therein, a piston slidable in the cylinder and
having a rod secured to one face, said rod
having a socket formed thereon, and a rod
secured to the valve and extending through
the elongated openings in the chamber and
cylinder, the lower end of said rod being
loosely received in the socket on the piston
rod.

In testimony whereof I affix my signature in presence of two witnesses.

LOUIE A. HOLST.
